BAFFLE GASIFIER

James L. Breese and Bruce Hayter, Santa Fe,
N. Mex., assignors to Oil Devices, Santa Fe,
N. Mex., a limited partnership of Illinois

Original application April 10, 1939, Serial No.
267,021. Divided and this application May 20,
1940, Serial No. 336,224

12 Claims. (Cl. 158—91)

Our invention relates to an improvement in pot type hydrocarbon burners. One purpose is the provision of improved means for preventing deposit of carbon or soot in the burner when the burner is running at low flame.

Another purpose is the provision of a maximum turndown whereby a pilot effect may be obtained.

Another purpose is the provision of improved gasifying means for obtaining the preliminary hydroxylation of the mixture in a pot type burner.

Another purpose is the provision of means for directing a mixture of primary air and vaporized hydrocarbon inwardly toward the central portion of a pot type burner.

Other purposes will appear from time to time in the course of the specification and claims.

The present application is a division of our co-pending application, Serial No. 267,021, filed on April 10, 1939.

We illustrate our invention more or less diagrammatically in the accompanying drawing wherein:

Fig. 1 is a vertical axial section; and

Fig. 2 is a section on the line 2—2 of Fig. 1.

Like parts are indicated by like symbols throughout the specification and the drawing.

Referring to the drawing, 1 indicates any suitable outer shell, drum or the like, into the interior of which any suitable means, not herein shown, may be employed for admitting air. 2 is a circumferential support which may be secured to the inner face of the member 1 and which is herein shown as a ring annular in cross section. 3 indicates the mixing chamber or pot proper, which may have a slightly concave bottom 4 and an oil or liquid fuel inlet member 5. The member 3 is shown as having an upper top flange 6 with a down-turned outer flange portion 7 adapted to seat upon the ring 2, whereby the burner pot is supported within the shell 1.

The pot is shown as being provided with a plurality of primary air inlet apertures 8 which may be located in rows at various levels. 11 indicates a top row of secondary air inlet apertures, the function of which is to supply additional or secondary air to the upwardly rising mixture of air and vaporized hydrocarbon.

Whereas the process of combustion does not of itself form part of the present invention, it will be understood that in the type of burner herein described a liquid fuel is supplied through the inlet or pipe 5. This liquid fuel is vaporized by the heat of combustion going on in the upper portion of the pot 3 or thereabove. As the liquid hydrocarbon is vaporized it rises upwardly to and past

the level of the various primary air apertures 8 and 10. These apertures serve as an air metering arrangement whereby only sufficient air is supplied to the vaporized hydrocarbon to form a preliminary mixture. It is not until the preliminary mixture receives the additional air supply which enters through the secondary air inlets 11 that final combustion takes place.

The above is a description of the operation of the device when it is being employed at relatively high heating capacity. It is desirable, in burners of this type, to provide for turndown means whereby a low or practically pilot flame may be employed. To obtain this result we supply a generally horizontal baffle member which includes a flat ring 12 having an inner aperture 13. The ring 12 is herein shown as terminating, as at 14, at a radial distance inwardly from the inner face of the pot 3.

The ring 12 may be a casting and is shown as having a downward extension 16, having an outer face 16, spaced substantially inwardly from the pot, and an inner face 17, which is located somewhat inwardly of the edge of the aperture 13. The ring structure may be formed of two parts, as shown in Fig. 1, which may be clamped together with any suitable screws or bolts 20, having, for example, Venturi portions 22. The Venturi apertures 24 are generally radial and horizontal and are each aligned with one of the primary air inlet apertures 10. It will be observed that the outer flange of the ring may be seated on pins or supporting members, shown at 23, inwardly extending from the wall of the shell or pot 3. The outer ends of the Venturi apertures 24 are inwardly spaced from the wall of the pot, and from the apertures in the wall of the pot with which they are aligned.

The baffle is so located in the pot 3 that the tubes or Venturi apertures are located directly opposite air holes in the pot. The jets of air that come from said holes 10 travel directly through the tubes as near as practically possible in the center.

As the air jets leave the holes in the pot they have a short free travel before actually entering the tubes or Venturi apertures. In order to align the Venturi apertures 24 properly with the apertures 10, we have provided an aligning bar 25, preferably welded to the pot 3, which is received in a corresponding slot 26 formed at the edge 14 of the ring 12.

If oil vapor is present, these air streams, due to their kinetic effect, will drag oil vapor radially inwardly along the tubes of the baffle structure. This oil vapor and air mixes thoroughly within

the tubes and a true hydroxylated oil gas is obtained. This hydroxylated gas is sufficiently rich under all conditions of operation and the velocity of the gas-air mixture in the tube is sufficiently above the rate of flame propagation to prevent flashing back. This gas-air mixture, as it leaves the tubes, burns with an almost clear blue flame.

All of these air jets, as they pick up the gas, create a slight vacuum in the chamber below the baffle or gasifier structure. This vacuum causes a part of the burning gas, as it leaves the ends of the tubes, to be drawn downwardly. This downward flow of hot gases keeps the bottom of the pot quite hot, recirculates the products of combustion, and pre-heats the carbon dioxide and oil vapor mixture. It has been frequently shown that the mixture of carbon dioxide and the pre-heating of the carbon dioxide gas mixture is advantageous from a combustion standpoint.

While the structure of Fig. 1 can be employed as a pilot, since, located in alignment with the lowest row of holes, it provides a low turndown, it is essentially a gasifier and a hydroxylator and can be located, if desired, at a higher level in the pot. The fact that it can burn at low capacity, due to excellent combustion characteristics, is incidental although desirable.

It will be realized that, whereas we have described and shown a practical and operative device, nevertheless many changes may be made in the size, shape, number and disposition of parts without departing from the spirit of our invention. We therefore wish our drawing to be taken as illustrative and diagrammatic, rather than as limiting us to our precise showing.

We claim:

1. In a pot type hydrocarbon burner, a pot having a bottom and a side wall, said side wall having therein a plurality of air inlet apertures located at various levels, means for delivering a liquid fuel to the bottom of said pot, and a gasifier intermediate top and bottom of said pot, said gasifier including a plurality of air and gas passages extending generally radially inwardly from a point adjacent but out of contact with the inner face of the pot and aligned with air inlet apertures in said pot, said passages having a length substantially exceeding their diameter.

2. In a pot type hydrocarbon burner, a pot having a bottom and a side wall, said side wall having therein a plurality of air inlet apertures located at various levels, means for delivering a liquid fuel to the bottom of said pot, and a gasifier intermediate the top and bottom of said pot, said gasifier including a plurality of generally radial air and gas passages, aligned with air inlet apertures in said pot, said passages having a length substantially exceeding their diameter, the outer ends of said passages terminating a short distance inwardly of the inner face of the side wall of the pot whereby, in response to the movement of air jets from said pot wall apertures into said passages, vaporized hydrocarbon present in the space below the gasifier is carried radially inwardly through said passages.

3. In a pot type hydrocarbon burner, a pot having a bottom and a side wall, said side wall having therein a plurality of air inlet apertures, means for delivering a liquid fuel to the bottom of said pot, and a gasifier structure located intermediate top and bottom of said pot, said structure including a plurality of generally radial air

and gas inlet passages located each in alignment with one of said air inlet apertures, the outer ends of said passages being in communication with the interior of the lower portion of said pot, said passages having a length substantially exceeding their diameter.

4. In a pot type hydrocarbon burner, a pot having a bottom and a side wall, said side wall having therein a plurality of air inlet apertures, means for delivering a liquid fuel to the bottom of said pot, and a gasifier structure located intermediate top and bottom of said pot, said structure including a plurality of generally radial air and gas inlet passages located each in alignment with one of said air inlet apertures, the outer ends of said passages being in communication with the interior of the lower portion of said pot, said passages terminating inwardly at a point radially outwardly spaced from the central axis of the pot, said passages having a length substantially exceeding their diameter.

5. In a pot type hydrocarbon burner, a pot having a bottom and a side wall, said side wall having therein a plurality of air inlet apertures located at various levels, means for delivering a liquid fuel to the bottom of said pot, and a gasifier structure located intermediate top and bottom of said pot, said structure including a baffle ring with its outer edge terminating adjacent the inner face of the pot, said baffle having a central aperture generally coaxial with the pot, and a plurality of generally radial air and gas inlet passages located each in alignment with one of said air inlet apertures, the outer ends of said passages being in communication with the interior of the lower portion of said pot, said passages terminating inwardly adjacent the axial aperture of said baffle, said passages having a length substantially exceeding their diameter.

6. As a new article of manufacture, a gasifier ring for pot type burners, including a ring of cast metal having inner and outer concentric edges, the inner edge defining an unobstructed central aperture extending entirely through the ring, and a downward extension, the outer edge of which is spaced inwardly from the outer edge of the ring, the inner edge of which is spaced inwardly from the inner edge of the ring, said downward extension having formed therein a plurality of radial passages.

7. As a new article of manufacture, a gasifier ring for pot type burners, including a ring of cast metal having inner and outer concentric edges, the inner edge defining an unobstructed central aperture extending entirely through the ring, and a downward extension, the outer edge of which is spaced inwardly from the outer edge of the ring, the inner edge of which is spaced inwardly from the inner edge of the ring, said downward extension having formed therein a plurality of Venturi radial passages.

8. In a pot type hydrocarbon burner, a pot having a bottom and a side wall, said side wall having therein a plurality of air inlet apertures located at various levels, means for delivering a liquid fuel to the bottom of said pot, and a gasifier intermediate top and bottom of said pot, said gasifier including a plurality of air and gas passages extending generally radially inwardly from a point adjacent but out of contact with the inner face of the pot and aligned with air inlet apertures in said pot, each said air passage having a Venturi neck therein, said passages having a length substantially exceeding their diameter.

9. In a pot type hydrocarbon burner, a pot having a bottom and a side wall, said side wall having therein a plurality of air inlet apertures, means for delivering a liquid fuel to the bottom of said pot, and a gasifier structure located intermediate top and bottom of said pot, said structure including a plurality of generally radial air and gas inlet passages located each in alignment with one of said air inlet apertures, the outer ends of said passages being in communication with the interior of the lower portion of said pot, each said air passage having a Venturi neck therein, said passages having a length substantially exceeding their diameter.

10. As a new article of manufacture, a gasifier ring for pot type burners, including a ring of metal having inner and outer concentric edges, the inner edge defining an unobstructed central aperture extending entirely through the ring, and a downward extension, the outer edge of which is spaced inwardly from the outer edge of the ring, the inner edge of which is spaced inwardly from the inner edge of the ring, said downward extension having formed therein a plurality of radial passages.

11. As a new article of manufacture, a gasifier ring for pot type burners, including a ring of metal having inner and outer concentric edges, the inner edge defining an unobstructed central aperture extending entirely through the ring, and a downward extension, the outer edge of which is spaced inwardly from the outer edge of the ring, the inner edge of which is spaced inwardly from the inner edge of the ring, said downward extension having formed therein a plurality of Venturi radial passages.

12. As a new article of manufacture, a gasifier ring for pot type burners, including a ring of metal having inner and outer generally concentric edges, the inner edge defining a central aperture extending directly upwardly and entirely through the ring, said ring having associated therewith a plurality of generally radial passages having a length substantially exceeding their diameter, the outer ends of said passages being spaced inwardly within the maximum diameter of the ring, the inner ends being located adjacent the central aperture of the ring.
